MARTIN C. BERSTED, OF SAN DIEGO, CALIFORNIA.

FLATIRON.

Application filed September 28, 1922. Serial No. 591,094.

My invention relates to electric flat irons, more particularly to automatic heat-regulating flat irons and the objects of my invention are: first, to provide a flat iron of this class which will be held at a substantially constant temperature when in use; second, to provide a flat iron of this class in which the heat will be automatically regulated, thus avoiding scorching of fabrics and also 10 reducing to a minimum the waste of time in waiting for the iron to heat up while engaging in ironing as is customary with the conventional iron; third, to provide an electric heating apparatus in which the electrical energy is automatically shut off when 15 a certain predetermined high temperature is reached; fourth, to provide an electric heating apparatus of this class in which the electrical energy is automatically turned on 20 when a certain low temperature is reached; fifth, to provide novelly constructed automatic electric heat regulating means; sixth, to provide novel means for adjusting said 25 automatic electric heat regulating means; seventh, to provide a novelly constructed handle for flat irons; eighth, to provide a novelly constructed electric flat iron, and ninth, to provide a flat iron of this class 30 which is very simple and economical of construction proportionate to its functions, durable, efficient, reliable, compact and which will not readily deteriorate or get out of order.

With these and other objects in view as will appear hereinafter my invention consists of certain novel features of construction, combination and arrangement of parts and portions as will be hereinafter described in detail and particularly set forth in the 40 appended claims, reference being had to the accompanying drawings and to the characters of reference thereon which form a part of this application, in which:

Figure 1 is a plan view of my flat iron; Fig. 2 is a side elevational view thereof; Fig. 3 is a longitudinal sectional elevational view thereof showing certain parts and portions in elevation to facilitate the illustration; Fig. 4 is a fragmentary horizontal sectional view thereof taken through 4—4 of Fig. 3 showing certain parts and portions in plan to facilitate the illustration; Fig. 5 is a fragmentary transverse sectional view taken through 5—5 of Fig. 3, also showing certain parts and portions in elevation; Fig. 6 is a fragmentary enlarged transverse sec-

tional view similar to that shown in Fig. 5; Fig. 7 is a fragmentary rear elevational view with certain parts and portions broken away and in section to facilitate the illustration; Fig. 8 is a fragmentary transverse sectional view taken through 8—8 of Fig. 3; Fig. 9 is a fragmentary rear elevational view of a slightly modified form of construction of my flat iron showing a different means of manual adjustment for certain specific heats and Fig. 10 is a fragmentary sectional view thereof taken through 10—10 of Fig. 9.

Like characters of reference refer to similar parts and portions throughout the several views of the drawings.

The base plate 1, insulating material 2, heating elements 3, upper plate 4, screws 5, casing 6, screw 7, handle supporting member 8, plate 9, handle 10, bolt 11, bracket 12, screws 13, thermostat member 14, diaphragm 15, retaining ring member 16, nut 17, circuit breaking member support 18, screw 19, terminal support 20, screw 21, terminal posts 22, insulating washers 23 and 24, conductors 25, 26 and 27, screws 28 and 29, conductor 30, adjusting screw 31, mercury 32, nut 33, the end support 34 and the screws 35 constitute the principal parts and portions of my flat iron structure in its preferred form of construction.

In my electric flat iron the base plate 1, the insulating material 2 which consists preferably of a series of sheets of mica, and the resistance heating elements 3 are of the conventional type and are positioned relatively to each other in the conventional manner. The upper plate 4 which is secured to the base plate by the screws 5 and positions the said heating elements between the same and said base plate is also similar to that of the flat irons now in use. The heating elements, the upper plate 4 and other members as will be described hereafter are

enclosed by a casing 6 which is positioned above the base plate 1 and is secured in said position by the hollow headed screw 7 which extends through the upper central portion of said casing into the upper plate 4. A boss 6a is provided on the under side of said casing surrounding the screw opening therein which spaces the upper portion of said casing from the upper plate 4 and prevents distortion of said casing when secured in position. A handle supporting member 8 is provided above the casing 6 and is secured thereto by means of the screw 7. Said

handle supporting member is provided with a bridged channel shaped portion 8^a at its lower end and is provided with downwardly extending lugs 8^b at said lower end which 5 are adapted to fit into corresponding slots 6^c in said casing for positioning said handle supporting member relatively thereto. Said handle supporting member is also provided at its lower central portion with a cup 10 shaped recess portion 8^c for the reception of the head of the screw 7. It will be noted that the handle supporting member 8 is so constructed at its lower portion as to provide ample circulation by air so as to 15 keep the same as cool as possible. A plate 9 which serves as a name plate for the flat iron is provided above the lower channel shaped portion of said handle supporting member to conceal the head of the bolt 7 20 and is secured to said handle supporting member as shown in Figs. 3 and 8 of the drawings by retaining lugs extending downwardly therefrom into slots in said handle supporting member. The handle 10 which 25 is preferably made of wood is secured to the upper ends of the upwardly extending arms 8^d and 8^e of the handle member 8 by the bolt 11 which extends therethrough and is secured in position by the nut 11^a. Said 30 handle 10 is provided with gradually curved slightly helical grooves 10^a which extend around the lower side of the same which are adapted to receive the fingers of the hand to facilitate the handling of the iron. 35 A bracket member 12 is provided within the rear portion of the casing 6 and is secured to the inner face of the same by means of the screws 13. Said bracket 12 is adapted to support the thermostat member 14 which 40 consists of a downwardly extending tubular portion 14^a at its lower end and an upwardly and outwardly extending curved flanged portion 14^b at its other end. Said thermostat member is slightly beveled at the periphery of its flanged portion and is also provided at the normally upper side and near the periphery thereof with an annular groove 14^c. A diaphragm 15 is positioned 45 over the upper portion of the thermostat member and is provided with an annular offset portion 15^a which corresponds with and extends into the annular groove portion of the thermostat member 14. The diaphragm 15 is also provided with an annular flanged portion which extends downwardly 50 over a portion of the bevelled outer edge of said diaphragm member. Said members 14 and 15 are secured together by an annular retaining ring member 16 which engages the upper portion of the diaphragm 15 at 55 its outer edge and extends around and below the outer edge of the flanged portion of the thermostat member. The tubular portion of the said member 14 is provided at its lower end with an internally threaded 60 portion 14^d which is adapted to receive the threaded portion 17^a of the nut 17. Said thermostat member is also tapered on its lower end and adapted to engage at said beveled end a correspondingly tapered recess 70 portion 17^b of the nut 17. A quantity of mercury 32 is provided in the tubular portion of the thermostat member 14 and extends up to and engages the diaphragm 15. The bracket 12 is provided on one side 75 with an upwardly offset and outwardly extending lug 12^a, and on the opposite side with a similar downwardly offset lug 12^b. A resilient circuit breaking member support 18 is secured to the upper portion of the lug 80 12^a by means of the screw 19, and extends over the diaphragm of the thermostat to the opposite side over the lug 12^b. Said bracket 12 is also provided at its rear portion with another lug 12^c extending upwardly therefrom and is adapted to support the terminal supporting member 20 which extends over the resilient circuit breaking member support 18 and the diaphragm 15 and is secured to the lug 12^c by the screw 21. Said 85 terminal supporting member 20 is also adapted to secure the thermostat member 14 in its supporting bracket 12. The terminal posts 22 extend upwardly from, and are secured to the terminal supporting member 20, 90 as shown in Fig. 3 of the drawing, and are insulated from said member by the insulating washers 23 which are positioned in countersunk recesses in the terminal supporting member and which position the 95 lower portions of the terminal posts centrally in the enlarged holes provided therein. The lower portions of the terminal posts extend therethrough and are secured in position to said supporting member 20 by the 100 nuts 22^a which are also insulated from the member 20 by the insulating washers 24. One of said terminal posts 22 is electrically connected to the screw 19 by the conductor 105 25, which screw extends through and is insulated from the lug 12^a of the bracket 12 and the circuit breaking member support 18, 110 and is connected at its lower end to the one end of the heating elements 3 by the flexible conductor 26, which is also insulated from the bracket 12 in the manner shown in Fig. 6 of the drawings. The other of the terminal posts is similarly connected by the flexible conductor 27, to a screw 28 which serves 115 as a circuit breaker and extends through and is insulated from the free end of the resilient circuit breaking member support 18 as shown best in Fig. 6 of the drawings. The screw 28 is provided at the end extending through the support 18 with a reduced circuit breaking point, preferably made of tungsten or platinum, and is adapted to engage a similar point provided at the end of the screw 29 which serves as the other circuit breaker member and extends through 120 125 130

the lug 12^b from the underside thereof and which is insulated therefrom, preferably as shown in the drawings. Said screw 29 is electrically connected to the other end of the 5 coils 3 by means of the flexible conductor 30. At the central portion of the resilient circuit breaking member support 18 there is provided an internally threaded lug 18^a which is adapted to receive and position the adjusting 10 screw 31, which is adapted to engage at its lower end the diaphragm 15, when raised by the expansion of the mercury 32 provided in the thermostat member 14 as shown by dotted lines in Fig. 6 of the drawing. A 15 lock nut 33 is provided on the adjusting screw 31 to lock the same in position relatively to the member 18 when adjusted to break the electrical circuit between the points of the screws 28 and 29 at a predetermined 20 high temperature. From the several views of the drawings it is seen that the casing 6 is so constructed as to conceal and enclose the conductors and circuit breaking and operating mechanism and thus reduce to a 25 minimum the possibility of an inexperienced person disturbing the proper functioning of the vital members of the apparatus. It will be particularly noted that the adjusting screw 31 is accessible from the outside only 30 through the small opening 6^c in the casing 6 and the opening 20^b in the terminal supporting member 20 by the special adjusting wrench means shown by dotted lines in Fig. 35 of the drawing. A support 34 is provided at the rear end of the iron for supporting the same on its end when not in use and is secured at its lower end to the base plate by the lugs 34^a extending downwardly from the lower portion of said support into recesses 1^a in the upper face of the rear portion of said base plate. Said support 34 is secured at its upper end to lugs 8^c which extend outwardly from the rear, upwardly extending arm 8^d of the handle member 8, by 40 means of the screws 35. Said support also serves as an enclosure for the lower rear portion of the iron and also as a guard for the terminal posts 22.

In the slightly modified form of construction of my electric flat iron as shown in Figs. 50 9 and 10 of the drawings I have provided an indicating member 36 which is provided at its inner end with a transversely positioned resilient sleeve 36^a which is adapted to receive therethrough the adjusting screw 31 which in this modified form of construction is slightly longer and is provided with threads having a greater lead than the one previously described. The resilient sleeve 55 50 of said indicating member is provided with outwardly extending lug portions 36^b which are adapted to receive the screw 37 for securing said indicating member to said adjusting screw. Said indicating member extends through transverse circular slots 6^a and 34^b at the rear portions of the casing 6 and end support 34 respectively. The portion of the indicating member extending through said slots is provided with a downwardly bent indicating finger portion 36^c 70 which is adapted to ride in the circular groove 34^c in said rear support and is adapted to be engaged by the hand of the operator and shifted to the various positions indicated by the letters L, M, and H impressed in 75 the support 34 adjacent to the groove therein, or any position intermediate said letters. It will be noted that in this modified form of construction the screw 31 is adjusted for an average heat and the indicating member 80 is then secured thereto, which indicating member permits of slight adjustment of the heat by the operator as desired when ironing or pressing thin or heavy fabrics. It will also be noted that in this modified form of construction the manual and easy adjustment of heat as desired will provide a more even temperature and will not break and close the electrical circuit as often, therefore 85 preserving the breaker points. 90

It is obvious that the indicating member shown in the modified form of construction may be used in conjunction with the adjusting screw and lock nut disclosed in the preferred form by positioning the lock nut 95 above the sleeve portion of the indicating member and adjusting the screw as previously described.

Though I have shown and described a particular construction, combination and arrangement of parts and portions and a certain modification thereof, I do not wish to be limited to the particular construction, combination, and arrangement nor to the modification, but desire to include in the 100 scope of my invention the construction, combination and arrangement, substantially as set forth in the appended claims.

It is obvious from the previous description and the drawings, that I have provided 105 an electric flat iron, which can be kept at a substantially constant temperature; that I have provided a flat iron of this class in which the heat will be automatically regulated; that I have provided an electric heating apparatus in which the electrical energy is automatically shut off when a certain predetermined high temperature is reached by the expansion of mercury in the thermostat 110 member 14, forcing upwardly the diaphragm 15 and disengaging the breaker portions at ends of the screws 28 and 29; that I have provided an electric heating apparatus of this class in which the electrical energy is automatically turned on when a certain low 115 temperature is reached; that I have provided a novelly constructed automatic heat regulating means; that I have provided a novel means for adjusting said automatic heat 120 regulating means; that I have provided a 125 130

novelly constructed handle for flat irons; that I have provided as a whole a novelly constructed electric flat iron, and that I have provided a flat iron of this class 5 which is very simple and economical of construction, durable, efficient and reliable, compact, and which will not readily deteriorate or get out of order.

Having thus described my invention, what 10 I claim as new and desire to secure by Letters Patent, is:

1. In a flat iron, a support, a stationary thermostat member positioned relative to said support, a yieldable thermostat member 15 mounted on said stationary thermostat member, a fluid heat expansible material positioned in said stationary thermostat member adapted to engage and exert a force on said yieldable thermostat member, and a circuit 20 breaking means positioned contiguous to and adapted to be actuated by said yieldable thermostat member.
2. In a flat iron, a support, a stationary thermostat member positioned relative to 25 said support and provided with a tubular portion, a thin, circular, suddenly yieldable thermostat member, an expansible fluid metal positioned in the tubular portion of said stationary thermostat member, adapted to expand longitudinally therein and engage and exert a force on said yieldable thermostat member, and a circuit breaking means positioned contiguous to and adapted to be actuated by said yieldable thermostat member.
3. In a flat iron, a support, a stationary thermostat member positioned relative to 35 said support and provided with a tubular portion, a thin, circular, suddenly yieldable thermostat member, and an expansible fluid metal positioned in the tubular portion of said stationary thermostat member, adapted to expand longitudinally therein and engage and exert a force on said yieldable thermostat member.
4. In a flat iron, a support, a stationary thermostat member positioned relative to 45

said support and provided with a tubular portion, a thin, circular, suddenly yieldable thermostat member, an expansible fluid metal positioned in the tubular portion of said stationary thermostat member adapted to expand longitudinally therein and engage and exert a force on said yieldable thermostat member, a stationary circuit breaking member mounted on said support, and a movable 55 circuit breaking member positioned contiguous to said stationary circuit breaking member and adapted to be shifted by said suddenly yieldable thermostat member.

5. In a flat iron, a supporting means, a 60 stationary thermostat member positioned relative to said supporting means, a yieldable thermostat member mounted on said stationary thermostat member, and a separate, fluid, heat-expansible material positioned in said stationary thermostat member adapted to exert a force on said yieldable thermostat member.

6. In a flat iron, a supporting means, a 70 stationary thermostat member positioned relative to said supporting means and provided with a tubular portion, a thin, circular, suddenly yieldable thermostat member mounted over and closing the one end of the tubular portion of said stationary thermostat 75 member, and a relatively expansible fluid metal positioned in said tubular portion, said fluid metal engaging with and adapted to exert a force on said yieldable thermostat member.

7. In a flat iron, a casing for said flat iron, a thermostat casing having an expandible head at one end, mercury in said thermostat casing, and a circuit breaking means positioned within said first casing and in operative relation with the expandible head of 85 said thermostat casing.

In testimony whereof, I have hereunto set my hand at San Diego, California, this 22nd day of September, 1922.

MARTIN C. BERSTED.
